UNITED STATES PATENT OFFICE.

SAMUEL MILBURN, OF KENNEDY, MISSOURI.

ATTACHMENT FOR SEED-PLANTERS.

1,072,632.

Specification of Letters Patent.

Patented Sept. 9, 1913.

Application filed June 16, 1913. Serial No. 773,977.

To all whom it may concern:

Be it known that I, SAMUEL MILBURN, citizen of the United States, residing at Kennett, in the county of Dunklin and State 5 of Missouri, have invented certain new and useful Improvements in Attachments for Seed-Planters, of which the following is a specification, reference being had to the accompanying drawings.

10 This invention relates to an attachment for planters and more particularly to a gage shoe whereby the seed may be evenly planted at a predetermined depth.

15 The invention has for its principal object to provide a device for the above purpose attachable to planters of the ordinary construction and which may be easily and quickly adjusted when it is desired to vary the depth of the furrow in which the seed 20 are deposited.

Another and more specific object of the invention resides in the provision of a single plate or casting longitudinally curved for engagement upon the forward edge of the 25 upwardly curved furrow-opening runner, said plate being provided with a central longitudinal slot in one end to receive the runner whereby the plate is held against transverse shifting movement, and means 30 for adjustably clamping the plate at its other end to the runner.

The invention has for a further object the provision of a planter attachment of the 35 above character which is exceedingly simple in construction, may be produced at small manufacturing cost and is highly durable, efficient and reliable in practical use.

With the above and other objects in view as will become apparent as the description 40 proceeds, the invention consists in certain constructions, combinations and arrangements of the parts that I shall hereinafter fully describe and claim.

For a full understanding of the invention, 45 reference is to be had to the following description and accompanying drawings, in which—

Figure 1 is a perspective view of a seed 50 depositing boot showing my improved attachment applied to the furrow-opening runner thereof; Fig. 2 is a horizontal section illustrating means for clamping the shoe to the runner; Fig. 3 is a section taken on the line 3—3 of Fig. 1; Fig. 4 is a detail plan view of one end of the shoe.

Referring in detail to the drawing, 5 des-

ignates a seed depositing boot which may be of any approved form, and 6 designates the furrow-opening runner or sword which extends forwardly from the lower end of the boot and is upwardly curved as at 7, said runner from its forward end extending rearwardly and upwardly to the upper end of the boot 5.

My improved shoe attachment embodies a 65 single integral casting or plate 8 which is longitudinally curved as shown and is of uniform width throughout its entire length. At one end of said plate, the same is provided with a central longitudinally extending slot 9, said slot opening upon the end of the plate and having its opposite edges 70 reversely inclined as indicated at 10 to provide a flaring entrance or mouth to said slot.

The shoe plate 8 adjacent its other or upper end is provided with spaced rectangular openings 11 to receive rectangularly formed shank portions of the bolts 12 which are loosely disposed in said openings. Upon these bolts, the clamping plate 13 is loosely 80 mounted, said plate having openings in its opposite ends to receive the bolt. This plate is preferably curved slightly, as shown, and upon the threaded ends of the bolts 12, the nuts 14 are engaged whereby the plate 85 13 may be forced into clamping engagement with the furrow-opening runner 7.

It is a well known fact that in order to obtain the best results in the planting of cotton, the seed must not be planted either too 90 deep or too shallow. It is therefore necessary, in view of the fact that the character of the ground varies in different places to adjust the furrow opener so that a furrow of the required depth will be formed in the 95 movement of the machine. Heretofore, a lever has been provided for this purpose and this lever is constantly actuated by the operator to suit the nature of the ground so that the seed will not be planted too deeply 100 in soft ground or too shallow in hard ground. In order to obviate this continual shifting of the adjusting lever and relieve the operator of considerable labor, I have devised my improved gage shoe above 105 described. After adjusting the gage shoe to the proper point upon the furrow-opening runner, so that said runner will be supported to form a furrow of the desired depth in accordance with the character of the 110 ground, further adjustment thereof is unnecessary, as the seed deposited from the

boot 5 into the furrow will be planted at the same depth in the movement of the machine over the field. By providing the broad flat plate extending upon opposite sides of the furrow opener, the same is prevented from sinking into the ground when soft places are encountered so that the planting of all of the seed at the same depth throughout is assured. The provision of 10 the slot 9 in the lower end of the shoe plate obviates all liability of transverse shifting or turning movement of the shoe upon the runner.

From the foregoing, it is believed that the 15 construction of my invention and the manner in which the same is to be used will be clearly and fully understood.

The device is extremely simple in its construction and may be easily and quickly attached to all types of planters now in general use without necessitating any alteration whatsoever in their construction.

The invention may also be produced at 25 very small manufacturing cost and will serve the purpose for which the same is devised in a highly efficient manner.

While I have above described the preferred form and construction of my invention, it will be understood that the same is 30 susceptible of many modifications without departing from the essential features or sacrificing any of the advantages thereof except as defined in the appended claims.

Having thus described the invention, what 35 is claimed is:

1. The combination with the furrow opener of a seed planter, of a gage shoe consisting of a longitudinally curved plate of

uniform width throughout its length adapted for engagement upon said furrow opener 40 and extending upon opposite sides thereof, and means for clamping said shoe to the furrow opener.

2. The combination with the furrow opener of a seed planter, of a gage shoe 45 comprising a longitudinally curved plate adapted for arrangement upon the forward lower edge of said furrow opener and to extend upon opposite sides thereof, said plate being provided with a longitudinal slot 50 in one end to receive the furrow opener, and means for adjustably clamping the plate at its other end to the furrow opener.

3. The combination with the furrow opener of a seed planter, of a gage shoe consisting of a longitudinally curved plate of 55 uniform width throughout its length, said plate being adapted for arrangement upon the forward lower edge of the furrow opener and to extend upon each side thereof and 60 provided with a central longitudinal slot in one of its ends, the open end of said slot being flared and adapted to receive the furrow opener, a pair of bolts loosely mounted in the opposite end of said plate and extending 65 upon each side of the furrow opener, a clamping plate loosely engaged upon said bolts, and nuts threaded upon the bolts to clamp said plate against the furrow opener.

In testimony whereof I hereunto affix my 70 signature in the presence of two witnesses.

SAMUEL MILBURN.
